UNITED STATES PATENT OFFICE.

LOUIS A. DÉSY, OF MONTREAL, QUEBEC, CANADA, ASSIGNOR TO JOSEPH WILLIAM HARRIS, OF MONTREAL, CANADA.

EXCAVATING APPARATUS.

No. 844,104.

Specification of Letters Patent.

Patented Feb. 12, 1907.

Application filed December 12, 1905. Serial No. 291,448.

To all whom it may concern:

Be it known that I, LOUIS ARSENE DÉSY, a subject of the King of Great Britain, residing at the city and district of Montreal, in the Province of Quebec, Canada, have invented certain new and useful Improvements in Excavating Apparatus; and I do hereby declare that the following is a full, clear, and exact description of the invention, such as will enable others skilled in the art to which it appertains to make and use the same.

My invention relates to excavating apparatus.

The object of my invention is to provide an excavating-bucket of the type commonly called "orange-peel" buckets with means of for digging in addition to the mere closing of its pivoted members.

A further object of my invention is to arrange the pivotal points of the members of the bucket with relation to a movable casing on a solid beam, so as to provide an efficient and easily-operated apparatus; and my invention consists of the construction, combination, and arrangement of parts as herein illustrated, described, and claimed.

In the accompanying drawings, forming part of this application, I have illustrated one form of embodiment of my invention, in which drawings similar reference characters designate corresponding parts, and in which—

Figure 1 is a side elevation of a construction-engine and of the apparatus of my invention, showing its application. Fig. 2 is a view of the bucket and its connecting parts, partly in section and partly in elevation, some of the parts being broken away and some of the parts being shown in a second dotted-line position. Fig. 3 is a view of a bucket and its connecting parts, partly in plan and partly in horizontal section. Fig. 4 is a view of the bucket-suspending means, partly in section and partly in elevation. Fig. 5 is a horizontal section through the bucket-suspending beam, and Fig. 6 is a sectional perspective of the extremity of one of the shells forming the bucket.

Referring to the drawings, 1 designates a construction-engine provided with winding-drums 2 and a derrick 3, to the latter of which is pivotally secured a friction-clutch 4, adapted to be opened and closed by the weighted lever 5, all of any suitable or ordinary construction.

Disposed in the friction-clutch 4 and adapted to be held thereby or released therefrom is a solid beam 6, preferably rectangular in cross-section. Slidably disposed on the beam adjacent its lower end is a flanged casing 7. Secured on the beam 6 above the flanged casing 7 are stops 8, adapted to limit the upward movement of the casing. Secured to the casing 7 is a rope or other flexible member 9, through the medium of which, acting in conjunction with the winding-drums 2, the casing may be raised, the casing and its connecting parts being actuated downward, as hereinafter described.

Secured on the lower end of the beam is a fixed bearing-plate 10, provided with four legs or lugs 11. Disposed on the opposite sides of the casing 7 are rotatable grooved pulleys 12, and secured on the opposite sides of the beam 6 are rotatable grooved pulleys 13. A rope or other flexible member 14 has its lower end secured, as at 15, to the bearing-plate 10 and is then passed successively around the grooved pulleys 12 and 13 and from thence to the winding-drums 2 of the construction-engine, by means of which the movable flanged casing 7 may be actuated downward. A suitable guide-roller 16 is placed on the casing 7, and another suitable guide-roller 17 is placed on the beam to guide the flexible member 14.

Suitable links 18 are disposed adjacent the lugs or legs 11 of the bearing-plate 10 and have their upper ends pivotally secured thereto and have their lower ends pivotally secured to extensions 19 on the upper and inner ends of the shells 20, forming the excavating-bucket. Each of the shells 20 is provided with a longitudinal strengthening-rib 21, disposed centrally of and on the outer surface thereof. Adjacent its sides each of the shells 20 is provided with ears 22, which are pivotally connected to the lower ends of braces 23, the upper ends of which braces are secured to the flanged casing 7. To provide a pivotal connection between the lower ends of the braces 23 and the ears 22 of the shells 20, the lower ends of the braces 23 are bifurcated, as at 24, and are formed each with two bearings 25, suitable pivots 26 being passed through the bearings 25 and the ears 22.

The pointed ends 27 of the shells 20 are of hardened material and may be secured to the shells by riveting or in any suitable way.

In the operation of my invention, the shells 20 being in the dotted-line position shown in Fig. 2, the beam 6 may be released from the friction-clutch 4 and actuated downward, so as to cause the pointed ends of the shells 20 to enter the material to be excavated. The rope or other flexible member 14 may then be wound on the drums 2 to cause the shells 20 to close and dig into the material to be excavated, the lugs 11 and links 18 forming the fulcrum and the power being applied through the braces 23 as the flanged casing 7 is actuated downward, the beam 6 being in the meantime held against upward movement by means of the friction-clutch 4 and the shells 20 finally assuming the full-line position shown in Fig. 2. The beam 6, carrying the excavating-bucket, may then be elevated from the excavation in the usual way and the bucket opened by means of the flexible member 9, which raises the casing 7 and again opens the bucket to the dotted-line position shown in Fig. 2.

Having thus fully described my invention, what I claim as new, and desire to secure by Letters Patent, is—

1. In an excavating apparatus, the combination comprising a beam, a casing slidably disposed on the beam, braces secured to the casing and provided with bifurcated lower ends having bearings thereon, a bucket comprising a plurality of members pivotally secured to the bearings on the lower ends of the braces, and pivotally connected with the beam, and means for raising and lowering the casing.

2. In an excavating apparatus, the combination comprising a beam, a casing slidably disposed on the beam, braces secured to the casing and provided with bifurcated lower ends having bearings thereon, a bucket comprising a plurality of members each provided with ears on opposite sides thereof, pivots connecting said ears to the bifurcated ends of the braces, a pivotal connection between the members of the bucket and the beam, and means for raising and lowering the casing.

3. In an excavating apparatus, the combination comprising a movable beam, means for locking the beam against movement a casing slidably disposed on the beam, a bucket comprising a plurality of members each having an extension thereon pivotally connected with the beam, a pivotal connection between each of said members and the casing, and means for raising and lowering the casing.

4. In an excavating apparatus, the combination comprising a beam, a casing slidably disposed on the beam, a bucket comprising a plurality of members, each provided with a

longitudinal strengthening-rib and each pivotally connected with the casing and the beam, and means for raising and lowering the casing.

5. In an excavating apparatus, the combination comprising a beam, a movable member on the beam, means for raising and lowering the movable member, a bearing-plate secured on the beam, and a bucket comprising a plurality of members, each pivotally connected with the casing and the bearing-plate.

6. In an excavating apparatus, the combination comprising a beam, a movable member on the beam, means for raising and lowering the movable member, a bearing-plate secured on the beam and provided with lugs thereon, links pivoted to the lugs, and a bucket comprising a plurality of members, each pivotally connected with the casing and pivotally connected with the links.

7. In an excavating apparatus, the combination comprising a beam, a casing movably disposed on the beam, grooved pulleys on the beam and the casing, a flexible member disposed over the pulleys and having one end secured to the beam, a bucket comprising a plurality of members pivotally connected with the casing, and the beam, and means for raising the casing.

8. In an excavating apparatus, the combination comprising a movable beam, a movable member disposed on the beam, a bucket comprising a plurality of parts each pivotally connected with the beam and the movable member, means for forcing the movable member downward and closing the parts of the bucket, means for raising and lowering the beam, means for locking the beam against movement and a flexible member secured to the casing and adapted to open the bucket.

9. In an excavating apparatus, the combination comprising a construction-engine, a friction-clutch carried by the engine, a solid beam disposed in the clutch, an "orange-peel" bucket carried by the beam, and means for opening and closing the bucket.

10. In an excavating apparatus, the combination comprising a solid beam, means for raising and lowering the beam, means for locking the beam against movement an "orange-peel" bucket on the beam, and means adapted to be operated independently of the raising and lowering of the beam and adapted to open and close the bucket.

In witness whereof I have hereunto set my hand in the presence of two witnesses.

LOUIS A. DESY.
